(57) **CLAIM**

The ornamental design for a toy figure, as shown and described.

DESCRIPTION

FIG. 1 is a front, top, left-side perspective view of a toy figure;

FIG. 2 is a front view thereof;

FIG. 3 is a rear view thereof;

FIG. 4 is a top view thereof;

FIG. 5 is a bottom view thereof.

FIG. 6 is a right-side view thereof; and,

FIG. 7 is a left-side view thereof.

The broken lines in the drawings depict portions of the toy figure that form no part of the claimed design.
